UNITED STATES PATENT OFFICE.

MORRIS HIRSHFIELD, OF BROOKLYN, NEW YORK.

DESIGN FOR A SLIPPER.

Application filed November 18, 1922. Serial No. 4,327. Term of patent 3½ years.

To all whom it may concern:

Be it known that I, MORRIS HIRSHFIELD, a citizen of the United States, residing in Brooklyn, in the county of Kings and State of New York, have invented a new, original, and ornamental Design for Slippers, of which the following is a specification, reference being had to the accompanying drawing, forming part thereof.

The drawing is a perspective view of a slipper embodying my design.

I claim:

The ornamental design for a slipper, substantially as shown.

In testimony whereof, I have hereunto subscribed my name.

MORRIS HIRSHFIELD.
